FOLDING MACHINE

Hermann Clare, Berne, Switzerland, assignor to
 "Promag" Progressa Maschinen A. G., Konol-
 fingen, Switzerland

Application March 5, 1941, Serial No. 381,810
 In Switzerland March 30, 1940

3 Claims. (Cl. 270—81)

The present invention relates to a folding machine for forming in sheets of paper, etc., two or more folds and is characterized by a set of two or more separably coupled folding apparatus each forming a self contained whole arranged to execute each one folding operation said apparatus being adapted to produce folds folded either forwards or backwards, parallel to each other or crosswise according to the manner of combining said apparatus.

In the drawings is represented an embodiment of a folding machine according to the invention and capable of forming three folds.

Fig. 1 shows diagrammatically in a plan the driving shaft of the machine.

Fig. 2 is a plan view of the machine.

Fig. 3 is a vertical section on line 3—3 of Fig. 2.

Fig. 4 a vertical section on line 4—4 of Fig. 2, and

Fig. 5 a vertical section on line 5—5 of Fig. 2.

The shown folding machine comprises four units, a driving apparatus A and three similarly formed folding apparatus B, C and D differing from each other only in size.

The framing 1 of the driving apparatus A is swingingly suspended to a horizontal axis 2 of an electro motor 3, which by a belting 4, 5, 6 drives a countershaft 7. Shaft 7 drives a shaft 9 by a toothed gearing 8 arranged below a table plate 1a of the feed table fast to the frame 1. A shaft 10 is arranged above said table and the shaft 9. Shaft 9 carries two fastened band moving rollers 11 and directly above the same shaft 10 two loose band guiding rollers 16 and beside each of these a swinging arm 12. These arms extend over the table plate 15 of apparatus B and carry at their free ends a roller 13. An endless belt 14 is slung around the rollers 13 and 16, the lower branch of which is gliding over the table plate 15. The rollers 11 bear from beneath against the band guiding rollers 16 or the bands 14 and move the same. Hereafter only the folding apparatus B is described and represented in detail because the folding apparatus C and D are similarly constructed as B. Similar parts in the drawings are marked with similar letters of reference in each folding apparatus on a rectangular bed plate 17 a horizontal through shaft 18 is arranged and at the same level and on both sides of said shaft two coaxial short shafts 19 and 19a. Shaft 18 carries at both ends a coupling head 20 which is flush with the respective border edge of the respective plate or apparatus. Likewise the two shafts 19 and 19a carry at their outer ends coupling heads 20a which are flush with the longi-

tudinal border edges of the respective plate. The coupling heads 20 and 20a of one and the same folding apparatus are formed exactly alike at their free face sides. They have there either a diametrical groove 21 or a diametrical key 22. In the shown embodiment the coupling heads of the folding apparatus B show grooves and those of apparatus C show keys and those of apparatus D again grooves, and so forth. The through shafts 18, 19 and 19a of all the folding apparatus are all arranged at the same level so that said shafts may all be coupled together at the one or the other of the two opposite sides. In order to secure the coupled apparatus against lateral displacement the bed plates of the one side have holes 23 and the plates of the other side pins 24. With a view of driving the shaft 19 or 19a of apparatus B by the driving portion A the latter is provided with a reducing gear 25 the driving shaft 26 of which may be coupled with the one or the other of the shafts 19 or 19a. The through shaft 18 of every folding apparatus carries a bevel wheel 27 gearing each with a bevel wheel 28 or 28a respectively of the shafts 19 and 19a. Shaft 19 is compulsorily in driving connection by means of a gear wheel drive 29 with the one folding roller 30 and by means of a chain drive 31, 32, 33, 34, 35, 36 with the other folding roller 37 and with the shafts 38 and 39. The roller 37 and the shafts 38 and 39 are in working connection by means of a gear wheel drive 40 with a roller 37a or shaft 38 and 39a relatively. The shafts 38, 38a, 39, 39a carry each a set of feed rollers 41 and 41a respectively by means of which folded paper sheets are fed between rollers 30 and 37 towards one side of the apparatus. 42 is a guide sheet disposed between the rollers 30 and 37a and adapted to effect the change of direction of the folded paper sheet from the roller passage 30, 37 to the roller passage 31, 37a. Between the lower guide rollers 37a, 41 and 41a there is a supporting metal sheet 43 whereby the folded sheet is guided in a horizontal direction. The spring rests of the movably held rollers and shafts have not been represented. A cam disk 44 is fast to shaft 19a and an angular lever 46 pivoted to a pin 45 and carrying a roller 47 is bearing against said disk. The angular lever 46 is hinged by a link 48 to a lever 49 fast to a shaft 50. A helical spring 51 attached to the bedplate of apparatus B is connected to link 48 thus securing the contact between lever 46 and cam disk 44 and with this together securing the operating of the lever mechanism 46, 48, 49 and shaft 50. This shaft carries two arms 52 supporting together the folding knife 53. Table

plate 15 possesses a passage opening 54 beneath the folding knife 53, through which a paper sheet extended on the table plate which is to be folded is introduced by the downward striking folding knife between the folding rollers 30, 37 so as to produce a fold. Two band guide rollers 16 are fast to shaft 39 and alongside of the same are arranged loose and revolvably are arranged arms 12 carrying each a slid able roller 13. Between the rollers 13 and 16 is arranged a slid able pressure roller 13a capable of pressing the band at the desired place down to the paper sheet. The folded sheets are fed by the bands 14 to the apparatus C if a further fold is to be executed on the paper sheet. The level of the apparatus C corresponds with the level of the horizontal sheet guide of the apparatus B, so that the sheets delivered between the rollers 41 and 41a of apparatus B slip upon the table plate of apparatus C.

For the same amount of level apparatus D is lower than apparatus C and if a further apparatus should be added to the folding apparatus D also this further apparatus would have to be at a lower level than D. An adjustable but not represented 'check' plate is provided in the usual manner upon the table plate of each folding apparatus to limit the advance movement of the sheet fed by the bands.

For producing two folds in a paper sheet the apparatus C is coupled to apparatus B and for producing three folds an apparatus D is coupled to apparatus C.

According as the fold has to be executed on the one or the other side of the sheet the driving portion A will have to be joined to the one or the other longitudinal side of the apparatus B and apparatus C or D respectively have to be joined to one or the other longitudinal side of the apparatus B or C respectively. As a consequence of this is that the folded sheet will travel to the one or to the other side. The passage from one apparatus to the other of the sheet to be deposited upon the table 1a of the apparatus is operated quite automatically.

It must still be remarked that changes may be made which will remain within the scope of the invention. Thus it is possible to fit the driving portion A with the pocket folding device much

used in folding machines where the paper sheets are already provided with one or two folds when they are fed to the first folding apparatus.

The described folding machine has the great advantage over other known machines that corresponding to the provided number and arrangement of folds in a parallel or a crosswise manner the required folding apparatus forming each a self contained whole may be coupled directly together in such a way that fold will be folded either parallel with another fold or crosswise to the same or be folded forwards or backwards according to the manner of combining said apparatus. Such a combined machine will be less bulky than the machines hitherto known.

What I claim is:

1. In folding machinery for producing in advancing paper sheets a number of folds, folded forwards or backwards, parallel or crosswise, the combination forming one operative machine, of as many folding apparatus as there are folds, and of one driving apparatus, rectangular bedplate for each apparatus, crosswise arranged driving means provided in each of the folding apparatus and coupling means integral with such driving means, one on each side of the four sides of the folding apparatus and arranged to establish operative connection between driving apparatus and folding apparatus and between these among themselves.

2. In folding machinery according to claim 1 and in combination, a self contained folding apparatus comprising a through driving shaft, two side shafts on two opposite sides arranged at right angles, bevel gearing as driving means between the three shafts arranged to operate the two side shafts rotatably in opposite directions and coupling members attached to the free ends of said shafts flush with the four border edges.

3. In folding machinery according to claim 1 and in combination, a driving apparatus comprising a feed table, an electro motor suspended underneath said feed table, a speed reducing gear, a coupling member of the same flush with the border edge of the bedplate of the apparatus, and means for guiding and transferring the sheets to the folding devices.

HERMANN CLARE.
